APPLICATOR FOR EAR PROTECTORS

Elwyn Stanton Russell, Belmont, Mass., assignor
to the Government of the United States of
America, as represented by the Secretary of
War

Application July 29, 1944, Serial No. 547,202

7 Claims. (Cl. 128—152)

This invention relates to an applicator and more especially to an applicator for inserting an ear plug in the external meatus of the ear.

A development in ear protecting devices has been an ear plug which is of somewhat tubular character and which is characterized by an opening or cavity at its outer extremity. The ear plug is preferably formed of a compliant material such as rubber, plastic, and the like, to avoid excessive pressures on the tender cartilage portions which immediately surround and define the ear canal. It is required that this ear plug be located in a relatively advanced position in an ear canal in spaced relation to the tympanum or eardrum. However, the tubular construction noted and the compliant character of the material combine to provide a member which is somewhat lacking in stiffness. When the ear plug is held between thumb and finger and pressed into the ear canal, it tends to collapse upon itself. This makes it difficult to locate properly the member in the ear canal.

It is therefore an object of the invention to provide an improved applicator for inserting a tubular ear plug in the external meatus of an ear. Another object of the invention is to devise application means for engaging within a tubular ear plug, with a view to temporarily imparting stiffness to the plug so that it may be correctly positioned in an advanced position in an ear canal. Still another object is to devise an applicator which may be readily disengaged from a tubular ear plug after the plug member has been correctly positioned. The invention is also directed to providing a simple, cheap and efficient applicator device which may be further utilized as a means of supporting and carrying ear plugs when these members are not in use.

The nature of the invention and its objects will be more fully understood from the following description of the drawing and discussion relating thereto.

In the accompanying drawing:

Fig. 1 is a side elevational view illustrating the applicator with cap elements and an ear plug indicated in an operative position;

Fig. 2 is a view in side elevation illustrating the applicator of the invention engaged within an ear plug;

Fig. 3 is a perspective view illustrating the applicator with the ear plug removed therefrom;

Fig. 4 is a view in end elevation of the applicator with its cap element removed;

Fig. 5 is a cross section taken on the line 5—5 of Fig. 1;

Fig. 6 is a side elevational view diagrammatically illustrating an ear in which an ear plug is located; and

Fig. 7 is a plan cross sectional view of an ear canal diagrammatically illustrating an ear plug located therein.

In general, the applicator of the invention includes a central body portion or base of cylindrical form. At either end of the body portion are provided a plurality of resilient prongs or tips. The prongs in a slightly compacted position are adapted to engage with an ear plug and they serve both as a means of stiffening the ear plug and pressing it into an ear canal in an advanced position. When the ear plug is not in use the prongs further function as a holder. Surrounding the prongs and ear plugs in spaced relation thereto are cap elements which, together with the central body portion, constitute a closed container for carrying the ear plugs.

Referring more in detail to the drawing, numeral 1 denotes a central body portion of cylindrical shape which may be formed of any desired material, such as rubber, plastics, fibrous materials, and the like. Extending around the periphery of the central body portion 1 is an annular rib 2, formed with flat sides 4 and a peripheral edge 3 which is scored with tiny grooves or otherwise roughened to provide a gripping surface. At points immediately adjacent the sides 4 of the rib 2, the body portion 1 is recessed to provide annular grooves 5 and 6.

Numerals 7 and 8 indicate cap elements which are adapted to slidably engage over the ends of the central body portion 1. The caps may, if desired, be formed with slots 10 and 11 to allow the caps to be slightly expanded in passing over the ends of the body portion and to provide for beadings 12 and 13, of the caps 7 and 8 respectively, being snapped into the grooves 5 and 6. In this position the edges of the caps rest against the sides 4 of the rib 2. The roughened surface of the rib provides a convenient means of gripping the applicator when removing one of the cap elements. I may also desire to provide a clip member 14 mounted on the cap 8 (Fig. 1) for securing the assembled unit inside a pocket.

Numerals 15 and 16 denote two sets of prongs formed at the right and left sides respectively of the central body portion 1, as viewed in Fig. 1 of the drawing. The prongs are preferably molded to constitute an integral part of this member and are characterized by a substantial degree of resiliency. The prongs have rounded tips 15a and 16a and preferably are formed with

an arcuate cross section, as may be more readily observed from an inspection of Figs. 4 and 5.

The arcuate prong portions are arranged in circumferentially spaced apart relation to one another with their outer peripheral surfaces lying in a circle which is concentric with respect to the circle represented by the periphery of the central body portion 1. The inner surfaces of the prongs 16 are concaved, and lie in the circumference of a relatively smaller circle. In addition, the prongs extend axially outward with the edges of each prong lying in parallel relation to the edges of an adjacent prong.

The prongs are designed to engage in an ear plug of tubular construction having a cavity which opens at the outer end of the plug. In the drawing, I have indicated one form of tubular ear plug 17 with which the applicator may be employed. As may be more clearly observed in Fig. 3, the ear plug 17 is formed with a resilient tip 18 and an eccentric lip 19. 20 indicates a tab member for use in removing the ear protector from an ear canal, and 21 refers to an opening or cavity at the outer end of the plug. Figs. 6 and 7 of the drawing illustrate an ear 23 and ear canal 24 in which the ear plug is designed to be used.

The prongs, of a respective set, are designed to engage resiliently within the opening 21 with a light pressure which will cause the plug to cling to the prongs and which will avoid permanent change in the size and shape of the opening. To effect this result the circumference of the circle in which the outer peripheral surfaces of the prongs lie, is made to exceed slightly the circumference of the opening 21. The rounded ends of the prong of a respective set are then compacted in a generally radial direction until they may readily enter the opening 21. Thereupon the prongs are inserted in the opening 21 and allowed to spring outward against the inner surface of the plug.

When thus engaged within the ear plug the prongs provide both a means of holding the plug in a fairly rigid state and a means of passing the plug into an ear to the desired extent. In carrying out this operation, a preferred method is to employ one of the cap elements 7 as a handle by leaving the element snapped into place about the central body portion 1, as is illustrated in Fig. 2 of the drawing. This allows the applicator to be supported in the hand while the thumb and finger are free to compress the prongs when desired. The plug and applicator prongs are then inserted in the ear canal and advanced to a point at which the lip 19 comes to rest against the ear. The prongs may then be slightly compacted while at the same time the thumb is held against the lip 19 and the prongs are disengaged from inside the plug without changing its position in the ear canal.

Figs. 6 and 7 diagrammatically illustrate the plug in an operative position in an ear. It will be observed that the tip 18 engages in the ear canal 24 at a point well beyond the point of reverse curvature of the ear canal and at the same time the lip 19 rests against the cartilage portion 25 (Fig. 7), which forms a stop for limiting the extent to which the ear plug is advanced in the ear. A correct location of the plug is further obtained by disposing the plug with the longer edge of the tab 20 in a substantially vertical position (Fig. 6). Both the lip 19 and the tab 20 serve as guides for indicating how to hold the applicator just prior to inserting the plug.

From an inspection of Fig. 7, it will be seen

that the ear canal 23, in a horizontal plane, is characterized by a reversely curved formation and in order to advance the ear plug 17 beyond the point at which the ear canal is thus reversely curved, a certain amount of rigidity is required. The prong members, when engaged within the opening 21 of the ear plug, provide this required rigidity and allow the tip 18 to become correctly located against the skin lining of the ear canal.

10. The resilient character of the prongs is advantageous from the point of view of engagement and disengagement, and makes it possible to secure positively the plugs in a position in which they are ready for use at all times. As noted 15 above, one of the caps may at any time be conveniently used as a holder and when both of the caps are in place there is obtained a simple and efficient container for holding a pair of ear plugs.

While I have shown a preferred embodiment 20 of the invention, the size and shape of the body portion and prongs may be changed in various ways, the number of the prongs may be varied, and they may be arranged in an offset manner, a single applicator tip may be employed, and various other modifications resorted to, in keeping 25 with the spirit of the invention as defined by the appended claims.

I claim:

1. A device of the character described, comprising 30 a cylindrical body portion having an annular rib centrally disposed therearound, cylindrical cap elements mounted around the ends of the body portion and detachably secured against the annular rib at either side thereof, a plurality of 35 prongs formed at the ends of the body portion, said prongs extending axially outward in spaced relation to one another and to the cap elements.

2. An applicator for ear plugs, said applicator comprising a cylindrical body, cap members detachably fitted around the ends of the cylindrical body, a plurality of sets of prongs located at either end of the cylindrical body, said prongs of respective sets being of a resilient character for the purpose of engaging within an ear plug in a 45 slightly compacted position.

3. An applicator for ear plugs comprising a base and resilient means located in the base for the purpose of engaging within an ear plug.

4. A device for holding and applying a tubular 50 ear plug, said device including a body portion, a plurality of sets of resilient prongs axially disposed at either end of the body portion, said prongs of respective sets being of an arcuate cross section and having their outer peripheral 55 surfaces lying in a circle, said prongs being adapted to be compacted into a substantially tapered position and to hold resiliently a tubular ear plug mounted around their extremities.

5. An applicator for holding and applying ear 60 plugs, said applicator comprising a body portion, a plurality of sets of resilient elements projecting from either end of the body portion, said resilient elements of respective sets adapted to be engaged in the open ends of ear plugs in a slightly compacted position, caps surrounding the ends of the body portion and resilient elements in spaced relation thereto to constitute a container.

6. A holder and applicator comprising, a central 65 body portion having intermediate its ends a cylindrical rib whose outer surface is suitable for manual engagement, sets of prongs of resilient material mounted on the sides of said body and forming an outer surface substantially cylindrical in shape on the sides and substantially 70 hemispherical in shape on the ends, ear plugs 75

each carried on the hemispherical end of one of said sets of prongs so as to be readily detachable therefrom, and caps each inclosing one of said ear plugs and having quickly detachable engagement with said body portion, whereby, when one of said caps is detached, the other can serve as a handle during the use of the body portion and of the prongs as an applicator to place the uncovered ear plug in an ear.

7. A device according to claim 6 in which the body portion and each of said caps have either grooves or beadings thereon, said grooves and beadings being adapted to interfit and yieldingly retain said caps on said body portion.
